COVER FOR CONTAINERS

Lydia B. Koch, New York, N. Y., and Andrew Bodor, Newark, N. J.; said Bodor assignor to said Koch

Application March 19, 1932. Serial No. 599,865

4 Claims. (Cl. 229—47)

This invention relates to improvements in covers for containers, and more particularly to lock covers.

Among the principal objects which the present invention has in view are: To provide an improved cover which will lock itself to the body portion of a container; to provide means on the cover which will readily adapt itself to the container; to lock the cover to the container by turning the cover upon the container; to secure simplicity of construction; operation and minimum cost to manufacture; and to obtain other advantages and results as may be brought out in the following description:

15 Drawings:

Figure 1 is an elevation of a container embodying our invention;

Figure 2 is a vertical sectional view shown as taken on the line 2—2 of Figure 1;

20 Figure 3 is a cross sectional view of the cover shown as taken on the line 3—3 of Figure 2.

Figure 4 is an enlarged fragmentary sectional view of the cover shown as taken on the line 4—4 of Figure 2.

25 Figure 5 is a perspective view of the locking means before applied to the cover;

Figure 6 is an elevation similar to Figure 1 with modified locking means;

Figure 7 is a view similar to Figure 2 taken on 30 the line 7—7 in Figure 6, embodying the modification of Figure 6;

Figure 8 is a cross sectional view shown as taken on the line 8—8 in Figure 7; and

35 Figure 9 is a perspective view of the modified locking means.

Description:

In one specific embodiment of the invention illustrated in said drawings, the reference numeral 10 designates a container in general, comprising a cover 11 and body portion 12. It may be here noted that the construction of the container 10 is of the type generally used to carry comestibles, such as coffee, milk, soup, and so forth. It is of sturdy construction, preferably 45 made of durable cardboard and cylindrical in shape.

We find it desirable in the construction of the container to provide a cover 11 which has a depending peripheral flange 13, and to construct 50 the flange as of two plies of material 14 and 15, the inner one 15 of which may be comprised of a separate piece of material in juxtaposition to the outer ply 14. As here shown, the container and its cover are cylindrical as a result of which 55 said inner ply 15 will be ring-shaped and prefer-

ably of a depth corresponding to the depth of the outer ply. In the finished construction of the cover, the inner ply or ring is a fixed or permanent part of the cover, being cemented, glued, or otherwise secured to the outer ply.

In order to irremovably secure the cover to the container upon being applied thereto, there are provided a plurality of locking means between the telescoped portions of the cover, and container. As here shown, each said locking means is carried by the cover 11 and projects inwardly from the flange 13 thereof. In the showing in the drawings each said locking means comprises a staple or the like 16, having spur-like ends 17 for securing the staple in place.

Preferably the spur-like ends 17 of the staple are clamped between the two plies of the cover flange 13, said ends being separated and directed in a circumferential direction. The connecting part of each staple 15 extends in a circumferential direction and rests against the face of the cover flange which will engage the container upon applying the cover thereto.

The staple 16 is furthermore provided with teeth or burrs 18 upon the connecting portion, 80 said burrs facing inwardly or in a direction toward the body portion 12 of the container when the cover 11 is assembled thereon. It is to be noted that the teeth or burrs 18 slope acutely in one direction with the shaping edge curved in 85 a concave manner, thereby increasing the acuteness of the point so as to better dig into or grip the body portion when the cover is to be locked thereto.

It may here be observed that in the actual 90 showing in the drawings we have provided a plurality of burrs 18 for each staple 16, all of said burrs facing in the same direction, but is not to be understood that the invention is limited in this respect, nor is it limited in the number or placement of the staples employed in connection with any one container and its cover.

We have found it desirable to utilize a plurality of staples and arrange them successively in a spiral path so as to tend to form a screw 100 thread in the material engaged thereby when the cover is applied with a twisting motion. Consequently, when applying the cover with a twisting motion, the same is advanced to its seated position and the burrs 18 thereupon lock 105 the cover securely in that seated position.

Obviously, the cover cannot be unscrewed because of the burrs, and cannot be rotated forwardly for removal because of the spiral arrangement of the several locking means, nor can it be 110

pulled directly off, because the burrs project into the material and will effectively resist the displacement transverse to themselves and longitudinally to the container. The cover or container 5 therefore have to be damaged in one way or other in order to separate them, which deters and probably effectively prevents re-use of the container.

As a further constructional feature of the invention, it is to be observed that the staples 16 10 may be applied to the inner ply or ring 15 of the cover before assembly within the cover. This enables the spurs 17 at the ends of the staple to be bent flatwise against the outside of the ring 15, and to be included between the two plies 14 15 and 16 in the finished cover. These spurs will therefore have a supplementary gripping action 20 to the adhesive employed between the two plies and prevent a relative twisting between those parts when the cover is twisted or attempted to be twisted with respect to the container.

In the modified construction shown in Figures 6 to 9, the container 10, cover 11 and body portion 12 may have the same construction as heretofore described and a plurality of locking means 19 may be applied to one of the telescoping surfaces in a spiral arrangement as described in connection with preceding figures of the drawing. The locking means of this modification as 30 shown, as a staple, the ends of which provide spurs 20 to engage the appropriate part for mounting the staple in place, whereas the burrs 18 of the preceding construction were pressed from the face of the staple, in the present instance we provide burrs 21 formed at the longitudinal edges of the staple projecting in planes 35 perpendicular to the face of the staple.

In the exact showing of Figure 9, it will be observed we are enabled to thereby provide burrs 40 at both longitudinal edges of the staple and also may provide burrs at both ends of the staple. All of these burrs preferably taper in a common direction and are shouldered in an opposite direction so as to effectively perform the functions 45 ascribed to the burrs 18 in the preceding de-

scription. The operation both as to applying the cover and as to locking the same will be performed in accordance with and in a like manner as in the preceding description.

We claim:

1. A container as characterized comprising in combination with a container body portion, a cover fitting said body portion, said cover being comprised of two plies, locking means clamped between the two plies and projecting through the wall of the inner ply adjacent the body portion, and burrs on said locking means for engaging the body portion.

2. A container as characterized comprising in combination with a container body portion, a cover fitting said body portion, said cover being comprised of two plies, a plurality of staples clamped between the two plies and projecting through the wall of the inner ply adjacent the body portion, and burrs on said staples for engaging the body portion.

3. A container as characterized comprising in combination with a container body portion, a cover fitting said body portion, said cover being comprised of two plies, a plurality of staples clamped between the two plies and directed in a circumferential direction, burrs on said staples and projecting through the wall of the inner ply adjacent the body portion for securing said cover to the body portion in locked condition.

4. A container as characterized comprising in combination with a container body portion, a cover fitting said body portion and applicable thereto by a screw motion, said cover being comprised of two plies, locking means clamped between the two plies and projecting through the wall of the inner ply adjacent the body portion, and burrs on said locking means for engaging the body portion, said burrs extending in a direction to permit said screw motion to apply to the cover but resisting reverse screw motion.
